INVENTOR

EDWARD McCRAW

BY

Wm. Emerson
ATTORNEY

UNITED STATES PATENT OFFICE.

EDWARD McCRAW, OF NORTH ADAMS, MASSACHUSETTS.

PICKER STICK.

Application filed April 10, 1923. Serial No. 631,120.

In looms, it frequently happens that the picker stick is caught or broken and it is therefore desirable that it be capable of yielding, particularly on the return stroke, to avoid breakage or stopping. However, the stick should be comparatively rigid on the forward or driving stroke, so as not to have any considerable lost motion that might result in an incomplete travel of the shuttle which the picker sticks drives. The stick usually operates a shuttle at the rate of about 114 times a minute, so that if the stick flexed backwardly too readily during the driving stroke, that rate of operation would not be possible.

An object of the invention is to provide an improved picker stick which will have little or no lost motion on the driving movement; which if caught will yield in order to avoid stopping or breakage; which is exceptionally light in weight, durable and inexpensive in construction, and rigid to flexure transversely of its plane of movement. Other objects and advantages will be apparent from the following description of an embodiment of the invention and the novel features will be particularly pointed out hereinafter in claims.

In the accompanying drawing:—

Fig. 1 is a perspective of a stick constructed in accordance with the invention.

Fig. 2 is a sectional elevation of the same.

In the illustrated embodiment of the invention, a strip of metal 1, such as of spring brass or sheet steel, is bent upon a face into the shape of a U, and a tubular holder 2, preferably also of suitable metal, is secured between and connects the free ends of the arms of the U, the holder being secured to the arms in any suitable manner, such as by screws or rivets 3. The holder is disposed with its axis endwise of the U, and is adapted to receive and support the peg 4 which may be of suitable material such as wood or metal preferably the former.

A bearing block 5 is secured between the arms of the U and adjacent the base thereof, in any suitable manner, such as by rivets or bolts 6, which pass through both the block and the arms of the U. The block is provided with an aperture 7 through which a supporting pivot shaft or pin (not shown) may pass for pivotally supporting the U for oscillation or rotation in the plane of the arms thereof.

A saddle block 8 is disposed between the arms of the U in the space between the bearing block 5 and the holder 2, the saddle block being secured to the forward arm, relatively to the shuttle driving movement, in any suitable manner, such as by screws 9. The forward edge 10 of the saddle block is preferably shorter than the space between the holder and the bearing block, but extends for the major portion of that space. The rearward edge 11 of the saddle block is shorter than the forward edge.

The upper end of the saddle block is tapered forwardly and upwardly from the rearward edge, so that if the peg is caught during its return movement the strips will flex upon the upper tapered end until the peg is released. During the forward or driving movement of the stick (shown by the arrow *a* in Fig. 1), the long edge of the saddle reinforces the U so that it will have little or no lost motion and also a slight amount of resiliency due to the slight space between the extreme upper end of the saddle block and the holder.

The lower end of the saddle block is preferably tapered forwardly, relatively to the driving movement of the stick, from the rear edge downwardly, so as to lighten the stick without materially lessening its rigidity during the driving movement. The taper at the lower end also allows a slight flexing of the arms of the U during the return or rearward movement of the stick if it is caught for any reason.

In use, the stick is mounted at the bearing block in the usual manner and a peg is secured in the holder at the upper end of the U. If for any reason the peg is caught, the strips of which the U is made will flex and thus release the stick, and if the peg should be broken it can be readily removed and replaced by a new one in a simple and expeditious manner, without highly skilled employees or expensive tools. The stick has considerable rigidity to lateral flexure because the strip forming the U will offer the greatest resistance to flexure on its edge. The saddle block provides the necessary rigidity on the driving movement. By varying the length of the saddle block the rigidity of the stick in its plane of movement can be varied. A stick constructed in accordance with this invention is practically indestructible.

It will be apparent that various changes in the details and arrangements of the parts herein described and illustrated for the purpose of explaining the nature of the invention, may be made by those skilled in the art within the principle and scope of the invention as expressed in the appended claims.

I claim:

- 10 1. A picker stick for looms comprising a bearing block, a peg holder, flat strips of metal connecting the block and holder, the planes of the strips being transverse to the plane of rotation of the stick, whereby the portions of the metal strips between the block and holder may flex somewhat within the plane of oscillation and be rigid in a transverse direction, and a saddle block confined between said strips and between the bearing block and peg holder, an end of the saddle block being tapered from one strip toward the other.
- 15 2. A picker stick for looms comprising a bearing block, a peg holder, flat strips of metal connecting and attached to the block and holder, the planes of the strips being transverse to the plane of rotation of the stick, whereby the portions of the metal strips between the block and holder may flex somewhat within the plane of oscillation and be rigid in a transverse direction, and a saddle block fitting between the flat strips and along the major portion of and less than the distance between the bearing block and peg holder.
- 20 3. A picker stick for looms comprising a bearing block, a peg holder, flat strips of metal connecting the block and holder, the planes of the strips being transverse to the plane of rotation of the stick, whereby the portions of the metal strips between the block and holder may flex somewhat within the plane of oscillation and be rigid in a transverse direction, and a saddle block fitting between the flat strips and along the major portion of the distance between the bearing block and peg holder.
- 25 4. A picker stick for looms comprising a bearing block, a peg holder, flat strips of metal connecting the block and holder, the planes of the strips being transverse to the plane of rotation of the stick, whereby the portions of the metal strips between the block and holder may flex somewhat within the plane of oscillation and be rigid in a transverse direction, and a saddle block fitting between the flat strips and along the major portion of the distance between the bearing block and peg holder, the upper end of the saddle block being tapered upwardly from the back edge to the forward edge whereby the strips have less resistance to flexure forwardly of the driving stroke than rearwardly of said stroke.
- 30 5. A picker stick flexible in the plane of its travel, and having a saddle block with a relatively reduced bearing surface at its rear side, whereby there is greater resistance to flexure in a rearward direction than in a forward direction relatively to the driving action of the stick, whereby the stick will drive the shuttle with little flexure and will yield more readily during the return movement.
- 35 6. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick.
- 40 7. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick, the lower end of the saddle block being tapered downwardly toward the forward edge.
- 45 8. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick, the lower end of the saddle block being tapered downwardly toward the forward edge.
- 50 9. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick, the lower end of the saddle block being tapered downwardly toward the forward edge.
- 55 10. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick, the lower end of the saddle block being tapered downwardly toward the forward edge.

planes of the strips being transverse to the plane of rotation of the stick, whereby the portions of the metal strips between the block and holder may flex somewhat within the plane of oscillation and be rigid in a transverse direction, and a saddle block fitting between the flat strips and along the major portion of the distance between the bearing block and peg holder, the upper end of the saddle block being tapered upwardly from the back edge to the forward edge whereby the strips have less resistance to flexure forwardly of the driving stroke than rearwardly of said stroke, the lower end of the saddle block being tapered downwardly from the back edge to the forward edge whereby the mass of the saddle block may be lessened without lessening the rigidity of the stick on the forward stroke.

11 12. A picker stick flexible in the plane of its travel, and having a saddle block with a relatively reduced bearing surface at its rear side, whereby there is greater resistance to flexure in a rearward direction than in a forward direction relatively to the driving action of the stick, whereby the stick will drive the shuttle with little flexure and will yield more readily during the return movement.

13 14. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick.

15 16. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick, the lower end of the saddle block being tapered downwardly toward the forward edge.

17 18. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick, the lower end of the saddle block being tapered downwardly toward the forward edge.

19 20. A picker stick comprising a strip of flat flexible metal bent upon a face into a substantial U-shape, a peg holder carried between and joining the free ends of the arms of the U, a bearing block secured to the base portion of the U, a saddle block between the arms of the U, spaced at the upper end from the holder, with upper end tapering forwardly and upwardly relative to the driving movement of the stick, the lower end of the saddle block being tapered downwardly toward the forward edge.

EDWARD McCRAW.
